COOKING IMPLEMENT

Robert H. Oppenheimer, 3410 Lake Shore Drive,
Chicago, Ill. 60657

Filed Feb. 25, 1974, Ser. No. 445,119

Term of patent 14 years

Int. Cl. D7—02

U.S. Cl. D7—102

FIG. 1

FIG. 5

FIG. 2

FIG. 3

FIG. 4

FIG. 1 is a top perspective view of a cooking implement showing my new design as embodied in a spatula;

FIG. 2 is a top view thereof;

FIG. 3 is a side view thereof, taken from the right side of FIG. 2;

FIG. 4 is a bottom view thereof; and

FIG. 5 is a fragmentary top perspective view of a cooking implement showing my new design as embodied in a fork, it being understood that the portion omitted for convenience of illustration is identical to that shown in the other views on the drawing.

I claim:

The ornamental design for a cooking implement, as shown and described.
